UNITED STATES PATENT OFFICE

159,536

CLIP-ON HAT RACK

David J. Rosenheim, New York, N. Y.

Application September 27, 1948, Serial No. 148,797

Term of patent 14 years

(Cl. D33—8)

To all whom it may concern:

Be it known that I, David J. Rosenheim, a citizen of the United States and residing at the city, county, and State of New York, have invented a new, original, and ornamental Design for a Clip-On Hat Rack, of which the following is a specification, reference being had to the accompanying drawing, forming part hereof and in which:

Fig. 1 is a top plan view of a clip-on hat rack showing the design of my invention.

Fig. 2 is a bottom plan view.

Fig. 3 is a side elevational view.

Fig. 4 is an edge elevational view.

I claim:

The ornamental design for a clip-on hat rack, substantially as shown.

DAVID J. ROSENHEIM.
